UNITED STATES PATENT OFFICE.

HARRY RALPH RICARDO, OF LONDON, ENGLAND.

FUEL PUMP OF INTERNAL-COMBUSTION ENGINES.

Application filed March 8, 1928, Serial No. 260,080, and in Great Britain April 13, 1927.

This invention relates to sleeve valve internal combustion engines employing liquid fuel injection and of the type in which each sleeve has a combined oscillating and reciprocating motion imparted thereto by means of a floating lever or beam to one point in which is imparted a substantially rotary motion by means of an eccentric or crank pin, a second point in the lever being connected to the sleeve, for example through a spherical or other flexible coupling, while the lever is constrained at a third point by a slide or by a link connected at one end to the lever and pivoted at the other end to the crank case or some other fixed part of the engine.

The object of the present invention is to provide improved mechanism for operating and controlling the fuel injection pump or pumps of such an engine.

According to the present invention the plunger of a fuel pump in an engine of the above type is operated through suitable mechanism from the floating lever or beam through which motion is imparted to the sleeve valve. When the invention is applied to a multi-cylinder internal combustion engine the plunger of each fuel pump is conveniently operated from the floating lever which actuates the sleeve valve in the cylinder to which the fuel pump delivers fuel. Other arrangements may, however, be employed if desired.

In either case when the floating lever or beam is constrained at one point by a pivoted link the plunger of the fuel pump is conveniently operated by such link while the suction valve or the suction valve and a separate spill valve controlling an overflow passage are operated by cams or eccentrics mounted on a rotary shaft driven from the crank shaft. This shaft conveniently also constitutes the pivot or fulcrum for the pivoted link. The engine is conveniently of the type in which the fuel is injected without atomizing air through a fuel injection device having an automatically operated fuel injection valve, the fuel pump being of the kind in which the middle portion of each pressure stroke only is employed to inject the fuel, the end portions of each pressure stroke being rendered in-

operative by opening the suction valve or a separate spill valve at such times.

The pump plunger is preferably adapted to be operated during its pressure stroke by the horizontal swinging motion of the floating lever or beam, in which case the arrangement is conveniently such that the beam is travelling with substantially its greatest horizontal velocity during the actual period of injection thus causing a correspondingly rapid injection of the fuel.

With an engine according to this invention it will be seen that the heavy shock-like loads imposed by the pump plunger when the operative portion of its pressure stroke takes place are taken by the relatively heavy sleeve operating linkage.

The invention may be carried into practice in various ways but one construction according to this invention is illustrated by way of example in the accompanying drawings, in which

Figure 1 is a cross-sectional elevation showing the operating mechanism for the fuel pump, and

Figure 2 is a similar view on an enlarged scale showing the construction of the fuel pump and the manner in which the valves are disposed and operated.

In the construction illustrated the engine comprises a water-cooled cylinder A having inlet and exhaust ports A¹, A² in its wall controlled by a sleeve valve B disposed and moving within the cylinder. Within the sleeve valve B reciprocates the piston C. The sleeve valve B has a combined oscillating and reciprocating motion imparted thereto by mechanism comprising a floating lever or beam D one end of which is connected, for example through a spherical joint or other flexible coupling, to the sleeve as indicated at E. To a point in the beam D intermediate in its length is imparted a rotary motion by means of a crank pin F on a crank shaft F¹, this crank pin engaging a suitable bearing in the beam D. The crank shaft F¹ is driven at half crank shaft speed through suitable gearing. The other end of the beam D is connected by a pivot G¹ to the end of one arm G² of a two-armed link or lever G pivoted at G³ to

some fixed part of the engine, this link serving to constrain the adjacent end of the beam D to move in an arcuate path. The other arm G⁴ of the link or lever G is connected by means 5 of a link H to a guide member H¹ reciprocating in a guide H² and connected by a member H³ to the lower end of the plunger J of a fuel injection pump.

The fuel pump plunger J passes through 10 a guide J¹ and operates within a suitable bore J² in a housing or casing J³. Formed in the upper end of the housing J² is the pressure chamber J⁴ of the pump, this chamber being closed by a screw-threaded cap J⁵ containing an automatic delivery valve J⁶ of 15 the ball type controlling the delivery of fuel through the delivery passage J⁷ leading to the fuel sprayer J⁸. Fuel is fed to the pressure chamber J⁴ through a suction or inlet 20 valve K of the poppet or like type controlling an inlet or suction passage K¹, the stem K² of this valve being provided at its lower end with a cap K³ against which bears a spring K⁴ tending to maintain the valve always closed. The suction valve K is adapted 25 to be opened positively by means of a push rod or tappet L controlled by a spring L¹ and adapted to be operated by an eccentric or cam L² on a shaft L³ which is driven by suitable 30 gearing from the crank shaft and serves also as the pivot for the link or lever G.

Between the upper end of the tappet L and the cap K³ on the lower end of the valve stem K² is disposed a tapered member M pivoted 35 at M¹ to a support M² which is capable of being rocked about a pivot M³ by means of a screwthreaded link M⁴ passing through a socket member M⁵ and provided with an adjusting screw M⁶ and lock nut M⁷. It will 40 be seen that by rocking the support M² the tapered member M can be moved so that it acts as a distance piece of different widths between the members K³ and L and thus varies the moment of opening and closing of the 45 suction valve K. If desired a second valve similar to K and operated in a similar manner by a cam or eccentric on the shaft L² may be provided acting as a spill valve controlling an overflow passage from the pressure chamber 50 of the pump, the suction valve or the suction and spill valves being so operated in known manner that only the centre portion of each pressure stroke of the plunger J is effective to deliver fuel through the valve J⁶ in the delivery passage.

It will be seen that with fuel pump operating mechanism according to the present invention, the heavy shock-like loads produced when the fuel pump plunger effects injection 55 of fuel are taken by the linkage mechanism for operating the sleeve valve which in any case has to be relatively heavy, thus removing the necessity for providing separate relatively heavy mechanism for operating the 60 plunger of the fuel pump.

It is to be understood that the constructional details may be varied without departing from this invention and that although the invention has been described with particular reference to engines in which the floating lever or beam is constrained at one point by a pivoted link, it may also be applied to engines in which one point in the floating lever is constrained to move substantially in a straight line by a slide or the like. 70

What I claim as my invention and desire to secure by Letters Patent is:—

1. An internal combustion engine of the liquid fuel injection type including in combination, a cylinder, a sleeve valve within the cylinder, a lever, means for imparting circular motion in a plane parallel to the cylinder axis to one point in the length of the lever, means for constraining another point in the lever to follow a determined path, a flexible operative connection between a third point in the lever and the sleeve whereby a combined oscillating and reciprocating motion is imparted to the sleeve, a fuel pump plunger, and an operative connection between the lever and the plunger whereby the plunger is caused to reciprocate in accordance with the movements of the lever. 80

2. An internal combustion engine of the liquid fuel injection type including in combination, a cylinder, a sleeve valve within the cylinder, a lever, a movable member which is constrained to follow a determined path, an operative connection between one point in the lever and this member, a means for imparting circular motion in a plane parallel to the cylinder axis to another point in the lever, an operative connection between a third point in the lever and the sleeve whereby a combined oscillating and reciprocating motion 90 will be imparted to the sleeve, a fuel pump plunger, and an operative connection between the plunger and the movable member whereby the plunger will be caused to reciprocate in accordance with the movements of the lever. 100

3. An internal combustion engine of the liquid fuel injection type including in combination a cylinder, a sleeve valve within the cylinder, a lever, a link pivoted at one end to a fixed part and at the other end to one point in the lever, means for imparting a circular motion in a plane parallel to the cylinder axis to another point in the lever, an operative connection between a third point in the lever and the sleeve valve whereby a combined oscillating and reciprocating motion will be imparted to the sleeve, a fuel pump plunger, and an operative connection between the plunger and the link whereby the plunger will be caused to reciprocate in accordance with movements of this link. 115

4. An internal combustion engine of the liquid fuel injection type including in combination a cylinder, a sleeve valve within the 120

- cylinder, a floating lever, a two-armed lever pivoted to a fixed part, a pivotal connection between one arm of the two-armed lever and a point in the floating lever, means for imparting circular motion in a plane parallel to the cylinder axis to another point in the floating lever, an operative connection between a third point in the floating lever and the sleeve whereby a combined oscillating and reciprocating motion will be imparted to the sleeve, a fuel pump plunger, and an operative connection between the other arm of the two-armed lever and the plunger whereby the plunger will be reciprocated in accordance with the movements of this lever. 5
5. An internal combustion engine of the liquid fuel injection type including in combination, a cylinder, a sleeve valve within the cylinder, a lever, a link pivoted at one end to a fixed part and at the other end to one point in the lever, means for imparting circular motion in a plane parallel to the cylinder axis to another point in the lever, a flexible operative connection between a third point in the lever and the sleeve valve whereby a combined oscillating and reciprocating motion will be imparted to the sleeve, a fuel pump comprising a cylinder, a plunger within the cylinder and at least one relief valve controlling an overflow port in the cylinder, an operative connection between the link and the plunger whereby the plunger will be caused to reciprocate in accordance with movements of this link, a cam shaft constituting a pivot for the fixed end of the link, means for rotating the camshaft and a cam on the camshaft acting on each relief valve so as to render the earlier and later portions of each plunger delivery stroke inoperative as set forth. 20
20. An internal combustion engine of the liquid fuel injection type including in combination a cylinder, a sleeve valve within the cylinder, a floating lever, a two-armed lever pivoted to a fixed part, a pivotal connection between one arm of the two-armed lever and a point in the floating lever, means for imparting circular motion in a plane parallel to the cylinder axis to another point in the floating lever, an operative connection between a third point in the floating lever and the sleeve valve whereby a combined oscillating and reciprocating motion will be imparted to the sleeve, a fuel injection pump comprising a cylinder, a piston within the cylinder and at least one relief valve controlling an overflow port in the cylinder, an operative connection between the other arm of the two-armed lever and the plunger whereby the plunger is caused to reciprocate in accordance with movements of the lever, a cam shaft acting as the pivot for the two-armed lever, means for rotating the camshaft and a cam on the camshaft acting on each relief valve so as to render the earlier and later portions of each pump delivery stroke inoperative as set forth. 25
7. A multi-cylinder internal combustion engine of the liquid fuel injection type including in combination a plurality of cylinders, a sleeve valve in each cylinder, a lever associated with each sleeve, an operative connection between one point in the lever and the sleeve, means for constraining another point in the lever to follow a definite path, a lay shaft, eccentrics on the lay shaft engaging respectively a third point in each lever, means for rotating the lay shaft whereby each lever will be caused to move so as to impart a combined oscillating and reciprocating motion to its associated sleeve, a separate fuel pump for supplying fuel to each cylinder comprising a cylinder and a plunger within the cylinder, and an operative connection between each plunger and the lever associated with the engine cylinder to which the fuel pump supplies fuel whereby the plunger is caused to reciprocate in accordance with the movements of the lever. 75
8. A multi-cylinder internal combustion engine of the liquid fuel injection type including in combination a plurality of cylinders, a sleeve valve in each cylinder, a lever associated with each sleeve, an operative connection between one point in the lever and the sleeve, a link, pivoted at one end to a fixed part and at the other end to another point in the lever, a lay shaft, eccentrics on the lay shaft engaging respectively a third point in each lever, means for rotating the lay shaft whereby each lever will be caused to move so as to impart a combined oscillating and reciprocating motion to its associated sleeve, a separate fuel pump for supplying fuel to each engine cylinder comprising a cylinder and a plunger within the cylinder, and an operative connection between each plunger and the link associated with the valve operating mechanism of the cylinder to which the fuel pump supplies fuel whereby the plunger is caused to reciprocate in accordance with the movements of the link. 85
9. A multi-cylinder internal combustion engine of the liquid fuel injection type including in combination a plurality of cylinders, a sleeve valve in each cylinder, a lever associated with each sleeve, a link associated with each lever and pivoted at one end to a fixed part and at the other end to one point in the lever, an operative connection between a second point in the lever and the sleeve, a lay shaft, eccentrics on the lay shaft engaging respectively a third point in each lever, means for rotating the lay shaft whereby each lever will be caused to move so as to impart a combined oscillating and reciprocating motion to its associated sleeve, a separate fuel pump for supplying fuel to each engine cylinder comprising a cylinder, a plunger within the cylinder and at least one relief valve controlling an overflow port in the cylinder, an operative connection be- 95

- 125

tween each link and its associated plunger whereby the plunger will be reciprocated in accordance with the movements of the link, a cam shaft constituting a pivot for the fixed ends of all the links, means for rotating the cam shaft and cams on the cam shaft acting respectively on the relief valves so as to render the earlier and later portions of each plunger delivery stroke inoperative as set forth. 10

In testimony whereof I have signed my name to this specification.

HARRY RALPH RICARDO.
